UNITED STATES PATENT OFFICE

FRANCIS HODGKINSON, OF SWARTHMORE, PENNSYLVANIA, ASSIGNOR TO WESTINGHOUSE ELECTRIC & MANUFACTURING COMPANY, A CORPORATION OF PENNSYLVANIA

TURBINE CYLINDER

Original application filed May 22, 1925, Serial No. 32,150. Divided and this application filed May 29, 1928.
Serial No. 281,526.

This application is a division of application, Serial No. 32,150, filed May 22, 1925 (since issued as Patent No. 1,682,338, August 28, 1928).

5 My invention relates to elastic fluid turbines, more particularly to turbines employing relatively higher pressures than have hitherto been commonly used, and it has for its object the provision of apparatus of the 10 character designated which shall be sturdy of design and efficient in operation.

A specific object is to provide a casing of greater strength than has heretofore been employed, and to bolt the parts of said casing 15 firmly together.

A further object is to provide means whereby a definite stress may be imposed on each bolt.

20 Apparatus embodying features of my invention is illustrated in the accompanying drawings forming a part of this specification in which:

Fig. 1 is a view in elevation showing a turbine made in accordance with my invention;

25 Fig. 2 is a longitudinal, vertical section of Fig. 1;

Figs. 3 and 4 are transverse sectional views taken through the turbine casing along the lines III—III and IV—IV respectively of 30 Fig. 1, said sections being at the exhaust outlet and motive fluid inlet respectively, but offset at the sides to show the bolt holes and the bolts in the casing; and,

35 Fig. 5 is a sectional view of a bolt employed in holding parts of the turbine cylinder together and including a heating element employed in accordance with my invention.

In the design of elastic fluid turbines employing relatively high initial pressures, for 40 example, upwards of 1000 lbs. per square inch, difficulties have been encountered in providing a casing capable of withstanding the high pressure therein without distortion in operation.

45 In accordance with my invention, I form the turbine casing or cylinder from two parts of suitable material, preferably two blocks of forged steel of approximately rectangular form. In order to secure the two halves together, I provide bolts, which may extend

the depth of the blocks, and I provide a hole from end-to-end in each of the bolts whereby they may be heated and tightened to provide a definite stretch of the bolts upon returning approximately to the temperature of the casing. At the exhaust end of the casing a deflector element is provided, and securing means therefor are arranged which also serve the purpose of staying the exhaust end of the turbine.

55 Referring now to the drawings for a more detailed description of my invention, I show, in Fig. 1, my improved turbine provided with motive fluid inlets 11—11 and with an exhaust outlet 12. Referring to Figs. 2 to 4, inclusive, the turbine 10 embodies a casing or cylinder 14 which is formed from two blocks of forged steel of approximately rectangular form, the blocks being bored out to form the cylinder as shown in Figs. 3 and 70 4. At 15, is shown a rotor which is provided with a plurality of rows of moving blades 16—16, for cooperation with alternate rows of stationary blades 17—17 carried by the cylinder 14. In order to hold the stationary 75 blades 17 in place, I provide grooves 18—18 bored out of the solid metal, into which the blade roots are inserted and wedged in place in any manner known to the art. At 18', I show a nozzle chamber in the form of a circular groove machined in the casing 14 and communicating with a nozzle block 20.

80 While I have illustrated a turbine having a solid rotor with rows of moving blades interleaving with stationary blades carried by the casing, it is within the purview of my invention to provide a rotor of the multiple disc type and mount diaphragms with nozzle elements in the grooves 18—18 in the casing.

85 The two halves of the casing 14 are held together by means of relatively long bolts 19—19 which may extend the entire depth of the casing 14, said bolts being provided at the top with nuts 21—21 and at the bottom 90 with nuts 22—22, the nuts 21 and 22 being screwed down tightly in order to hold the two halves together and to withstand the high pressure employed in the turbine. As 95 these bolts are necessarily large, I have found 100

them difficult to tighten with assurance of imposing thereupon definite stresses.

In order to more firmly secure the halves of the casing together, I provide means for heating the bolts 19 before the nuts 21 and 22 are tightened thereon, and also means for measuring the stretch of the bolts in order that a definite and uniform stress may be placed thereon. To this end, each bolt is provided with a hole 23 extending longitudinally therethrough, preferably centrally of the bolt and from end to end, and with plane surfaces accurately machined on the ends thereof.

Each bolt is tightened and the stretch thereof determined in the following manner: Micrometer measurements of the length of the bolt are made by applying a micrometer to the plane surfaces on the ends. A heating element, for example, an electric heating element 24, is placed within the hole 23, as shown in Fig. 5, and an electrical current is passed through it until the bolt is sufficiently heated.

One or both of the nuts 21 and 22 are turned a sufficient amount to provide the desired stretch. The amount that the nuts must be turned can readily be estimated, since the physical characteristics of the bolt material and the pitch of the thread are known.

After the nuts are tightened by being turned the correct amount, the bolt is allowed to cool, and the length of the bolt is again measured to check the stretch. If it has not been stretched the proper amount to provide the desired stress, the bolt is again heated and one or both of the nuts 21 and 22 turned to correct the amount of stretch. After cooling, the stretch may again be checked.

As noted above, the stress imposed upon the bolts, which is the force with which the bolts hold the halves of the casing together, is determined from the amount of stretch. By uniformly stressing the bolts, the casing parts are evenly secured together and the possibility of leakage minimized.

At the exhaust end of the turbine, I provide a deflector element 25 in the form of a ring surrounding the rotor 15 and resting in appropriate grooves formed in the exhaust end of the casing 14. In order to hold the deflector ring in position and to stay the exhaust chamber against the relatively high exhaust pressure, I provide bolts 25'-25", a suitable number of which extend longitudinally of the turbine cylinder through the exhaust chamber and the deflector ring 25 as shown.

At 26, Fig. 2, I show a dummy piston formed on the rotor 15 and having labyrinth packing elements 27 cooperating with similar elements carried by the casing 14 in order to prevent leakage thereby. Such leakage as does occur past the dummy piston 26 may be carried out through a conduit 28.

To prevent an unsafe pressure within the

turbine casing and in the exhaust pipe 13, I may provide a safety valve 53 on the header 47 which opens upon the attainment of a predetermined pressure within the casing 14 or the exhaust pipe 13, relieving pressure therein. 70

From the foregoing, it will be apparent that I have invented an improved elastic fluid turbine capable of withstanding pressures relatively higher than have hitherto been employed, and the halves of which are firmly bolted together. 75

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims. 80 85

What I claim is:

1. In a turbine, a casing formed from blocks of forged steel, a motive fluid inlet in the casing, an exhaust outlet for the casing, a deflector for the exhaust outlet and disposed within the casing on the discharge side of the last blade row, and securing means adapted to hold the deflector in place and stay the exhaust outlet. 90 95

2. In a turbine, a casing formed from blocks of forged steel, a motive fluid inlet in the casing, an exhaust outlet at one end of the casing, a deflector for the exhaust outlet and disposed within the casing on the discharge side of the last blade row, and bolts extending longitudinally of the casing through the deflector for holding it in place and for staying the exhaust outlet. 100 105

3. In a turbine, a casing formed from blocks of forged steel, a motive fluid inlet in the casing, an exhaust outlet at one end of the casing, a diffuser comprising a deflecting ring surrounding the rotor and supported within the casing opposite the exhaust outlet, and bolts extending longitudinally of the casing through the diffuser for holding it in place and staying the exhaust outlet. 110 115

4. An elastic fluid turbine having a casing formed in two parts from blocks of steel, and bolts for holding the parts of the casing together, said bolts having hollow interiors extending for the major portion of the length thereof for the insertion of heating means. 120 125

5. An elastic fluid turbine having a casing formed in two parts from blocks of forged steel, said casing having interior grooves formed in the solid metal for the insertion of turbine elements, and bolts extending the depth of the casing for holding the parts together, said bolts having hollow interiors extending for the major portion of the length thereof. 125

6. An elastic fluid turbine having a casing 130

formed in two parts from blocks of steel, said casing having interior grooves formed in the solid metal for the insertion of stationary turbine elements, and hollow bolts extending through the casing the entire depth thereof for holding the parts together, the hollow interiors of the bolts being adapted for the reception of heating means.

5 In testimony whereof I have hereunto subscribed my name this fourth day of May
10 1928.

FRANCIS HODGKINSON.
